UNITED STATES PATENT OFFICE.

HANS THIELSEN, OF WALLA WALLA, WASHINGTON TERRITORY.

RAILROAD CROSS-TIE.

SPECIFICATION forming part of Letters Patent No. 242,850, dated June 14, 1881.

Application filed November 13, 1880. (No model.)

To all whom it may concern:

Be it known that I, HANS THIELSEN, of Walla Walla, Washington Territory, have invented a new and useful Improvement in Railroad Cross-Ties, of which the following is a specification.

My invention relates to rolled-iron cross-ties for sustaining in position the track-rails upon the permanent way or road-bed of a railroad. 10 Each tie is made of T-iron, in two parts, secured together by a key, bolt, or other equivalent fastening, so as to make a slightly-flexible joint, all as more fully hereinafter described.

Referring to the accompanying drawings, 15 Figure 1 is a plan view, showing two of the ties with the rails in position thereon; Fig. 2, a side elevation of one of the ties, the rails being cut in the line *x x*, Fig. 1; Fig. 3, a perspective of a half-tie on an enlarged scale; Fig. 20 4, a section on line *y y*, and Fig. 5 a detail view.

Each tie is composed of two parts or halves, A A, with overlapping ends, secured together by a key, *a*, or other equivalent fastening device. Each half-tie A supports one of the rails, and is made of rolled T-iron, with a slot, *b*, at either end, and fingers *c*, adapted to firmly clasp the rail. These fingers are formed by slitting the edge and bending up the metal, as shown 25 in the drawings; or they may be cut out near the center and within the margin of the bar. After the rails are in position the fingers are bent down, so as to firmly secure them. One end of the key *a* is passed through the slots *b* 30 and turned a quarter-revolution to secure the parts together, and it is prevented from coming out by tamping the dirt about the lower end underneath the tie. The vertical member

of the T-bar is cut away toward the ends, thus leaving the greater weight of metal underneath 40 and adjacent to the rail.

In practice I may make the ties from an H-bar by cutting the web which unites the two upright members of the H-shaped bar in such a manner as to form the vertical member of 45 the tie. In this way great economy of material is effected, there being no waste except the half of a half-tie, which comes off at the end of the bar.

The advantages of my cross-tie are its cheapness and simplicity, and connecting the parts together by a flexible joint allows for the settling of the embankment under the rails without straining the tie or displacement of the rails.

I am aware that a cast-iron rail-supporting plate with a transverse stiffening-web on the under side, such plates being joined by rods transversely to the track, is not new, being shown in the English Patent No. 1,329 of 1850. 60 I therefore do not claim such device.

Having thus described my invention, what I claim is—

1. The half-tie A of rolled T-iron, having the slots *b* and fingers *c*, substantially as described.
2. The cross-tie of rolled T-iron, made in two parts and secured together by a flexible joint, substantially as described.
3. The cross-tie of rolled T-iron, having slots *b*, fingers *c*, and made in two parts, secured together by key *a*, substantially as described.

H. THIELSEN.
